UNITED STATES PATENT OFFICE.

EDWIN E. BARNEY, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 920,521.

Specification of Letters Patent.

Patented May 4, 1909.

Application filed November 21, 1905. Serial No. 288,440.

To all whom it may concern:

Be it known that I, EDWIN E. BARNEY, a citizen of the United States, and resident of Syracuse, in the county of Onondaga and 5 State of New York, have invented certain new and useful Improvements in Type-Writing Machines, of which the following is a specification.

My invention relates to tabulating mechanisms for typewriting machines and has for its main object to provide a simple and effective tabulating mechanism, wherein the actuation of a key will interpose a stop mounted on the frame of the machine in the 10 path of the carriage and will effect the release of the latter so that it may be arrested at predetermined points for column or tabulating work. To the above and other ends, the invention consists in the features of construction, combinations of devices and arrangements of parts hereinafter fully described and particularly pointed out in the 15 claims.

In the accompanying drawings, Figure 1 20 is a vertical, longitudinal sectional view of so much of a typewriting machine as is necessary to clearly illustrate my invention, parts of the machine being omitted. Fig. 2 is a rear elevation of the machine, certain of the 25 parts being omitted. Fig. 3 is an enlarged fragmentary rear elevation, partly in section, of the stop rack bar and its supports. Fig. 4 is an enlarged sectional side view showing the platen, platen carriage and certain of the 30 parts of the tabulating mechanism. Fig. 5 is an enlarged fragmentary top plan view showing the tabulating stop on the frame of the machine and the stop rack bar, one of the stops being shown on said rack bar.

I have shown my invention as applied to 35 a machine generally resembling the Monarch typewriter, but it is to be understood that said invention may be adapted to other forms of writing machines.

Referring more especially to Figs. 1 and 2, 40 1 indicates the base of the machine supporting corner posts 2, which, in turn, sustain a top plate 3. Key levers 4 are fulcrumed on a fulcrum plate 5 and each key lever is provided with a restoring spring 6. Pivoted at 45 7 to each key lever is a sub-lever 8, the lower portion whereof is slotted to coöperate with a fixed abutment 9 and the upper end whereof is connected by a connecting link 10 with 50 a type bar 11 pivotally mounted in a hanger

12, said hanger being secured by a screw 13 to a segmental type bar support 14 and being one of a series of hangers similarly secured to said support in an arc of a circle. The free ends of the type bars are normally supported by a segmental type rest 15 and said type bars are adapted to coöperate with the front face of a cylindrical rotary platen 16 which is mounted in a platen carriage, said platen carriage comprising side bars 17 and a rear bar which latter comprises oppositely disposed grooved rails 18 connected near their ends by web portions 19. Antifriction balls 20 are seated in the grooves in carriage rails 18 and coöperate with oppositely disposed grooved guide rails 21 and 22, said guide rails being secured by screws 23 to brackets 24 fixed to the top plate of the machine. A feed rack 25 is secured at its ends to arms 26 which are pivoted at 27 in the side bars 17 of the carriage and said feed rack is normally maintained by gravity and a rack spring (not shown) in mesh with a feed pinion 28 fixed at the forward end of a short shaft 29, said shaft being journaled in a 60 bracket 30 fixed to the top plate. Operatively connected with the rear end of the shaft 29 is an escapement wheel 31 and adapted to co-act with said escapement wheel are feed dogs 32 mounted at the top 65 of a pivoted dog rocker 33 which dog rocker is provided with a horizontally disposed arm 34. A link 35 connects the dog rocker arm 34 with a universal bar frame 36 pivoted at 37 in the base of the machine and carrying a universal bar 38 which extends from side to side of the machine beneath the series of key levers and the spacing levers (not shown) and is adapted to be depressed by said levers during printing and spacing operations. 70 The carriage is provided with a depending pin or lug 39 to which is secured one end of a band or strap 40, the other end whereof is secured to a carriage spring drum 41; said spring drum constantly tending to draw the 75 carriage leftward across the top plate of the machine. The depression of the universal bar during printing and spacing operations, causes the above described members of the escapement mechanism to coöperate in a 80 known manner to permit the carriage to be drawn to the left a letter space distance at a time under the influence of the spring drum. When the carriage rack 25 is lifted out of 85 mesh with the feed pinion 28 the carriage is 90

100 105 110

released from its escapement mechanism and may be drawn freely leftward under the influence of said spring drum.

As appears most clearly in Figs. 3 and 5, my tabulator mechanism comprises a rack bar or rod 42 formed on its front and rear sides with slots 42^a a letter space distance apart and mounted in ears 44 projecting rearwardly from angled brackets 44^a, said brackets being secured fixedly to the web portions 19 of the carriage by headed screws 45. The top of the rack bar 42 is preferably provided with a scale corresponding with the carriage scale and one or more column stops 15 43 may be mounted on said bars, the stops being bifurcated to engage the notches or serrations 42^a and being provided with contact portions 43^a. As viewed from the rear of the machine the left end of the rack bar 42 is reduced as indicated at 46 (Fig. 3), the reduced portion forming a shoulder 47 with the body of the rod. A headed bushing 48 surrounds the reduced portion 46, the bushing being externally threaded and being received in a threaded opening in the left-hand bracket ear 44. A locking nut 49 serves to secure the bushing in a fixed position after it has been properly adjusted. The inner end of the bushing is formed with a hole 50 30 which receives a coiled spring 51, the inner end of said spring abutting against the shoulder 47 on the rack bar 42. A headed screw 52 is received in a threaded opening in the end of the reduced portion 46, the head of said screw being normally maintained seated in a countersink in the end of the bushing 48 by the pressure of the coiled spring 51 which normally tends to press the rack bar 42 in printing direction. The other end of the 40 rack bar 42 is provided with a groove 53 and engaging said groove is a key 54 which is seated in a slot in the bearing opening in the bracket 44. The construction is such that the rack bar 42 is capable of longitudinal 45 movement but is held from rotary movement by the tongue and groove connection provided by the key 54 and groove 53. As will be noted from an inspection of Figs. 1 and 4, the bracket ears 44 project rearwardly 50 so that the rack bar 42 is held some distance from the rear of the carriage. The supporting brackets 24 of the guide rails 21 and 22 are curved rearwardly a sufficient amount to permit the free and unobstructed movement from side to side of the machine of the bar 42 and its bearing ears 44, and also of the 55 column stops 43.

As best shown in Fig. 5 a bracket 55 is secured to the rear face of the upper guide rail 21 by headed screws 56. The front face of the bracket 55 is provided with a projecting portion 55^a which enters a slot or depression 57 in the rear face of the guide rail 21, the construction being such that the 60 bracket 55 is thereby properly centered or

positioned. Ears 58 project rearwardly from the bracket 55 and said ears are perforated to receive a short shaft 59 upon which is pivotally mounted a tabulating stop designated as a whole by the numeral 70 60 and comprising a hub portion 61, a rearwardly and downwardly extending stop portion or arm 62 and a forwardly extending arm 63. The stop portion 62 is provided with a reinforcing rib 64 and secured to its 75 face by a screw 65 is a hardened steel plate 66, the head of the screw 65 being flush with the face of the plate 66 which latter is perforated to receive the shaft 59. This construction enables the stop member 60 to be 80 made of cast metal. One end of the top portion of the stop member is reduced as indicated at 67, said reduced portion abutting one of the ears 58 and being surrounded by a coiled spring 68, one end of which engages one of the bracket ears 58 and the other end of which enters a hole in the arm 63 of the stop member. The other end of the hub portion 61 of the stop member abuts against a boss 58^a formed on the inner end 90 of the adjacent bracket ear 58. The construction is such that while the tabulating stop may turn freely on its pivot it is held from endwise movement by the abutting bracket ears 58. The forward end of the 95 arm 63 is provided with a lug 63^a and the spring 68 tends to maintain said lug in contact with the top of the bracket 55. The under edge of the arm 63 is formed with a 100 notch 63^b (Fig. 5).

Engaging the notch 63^b in the stop arm 63 is a stop lifter 69, the lower part of which is bifurcated, the bifurcated portions being secured by screws 70 to the arms of a bifurcated rack lifter 71. The arms of the rack lifter are disposed one at each side of the shaft 29, the journal or bracket 30 being cut away to guide and support said rack lifter. The bifurcations of the rack lifter are bent forward horizontally, forming lifting shoes 110 72 which stand normally beneath and out of engagement with the feed rack 25. The stop lifter 69 is an extension from the rack lifter and the two may if preferred be formed from a single piece of metal instead of two 115 pieces rigidly fastened together. The lower end of the rack lifter is pivotally connected at 73 with a lever 74 fulcrumed at 75 in a lug 76 depending from the top plate of the machine and provided with a restoring 120 spring 77. The other end of the lever 74 is pivotally connected at 78 with the upper end of a vertically disposed link 79, the lower end whereof is pivotally connected at 80 with a tabulating key lever 81 pivoted at 82 in the 125 base of the machine and provided at its forward end with a tabulating key 83 which, it will be noted from an inspection of Fig. 1, is in the regular keyboard of the machine.

In assembling the parts the rack bar 42 is 130

properly adjusted by means of the threaded bushing 48. It will be understood that for any desired form of tabular work the necessary number of stops 43 are placed in the proper positions on said rack bar. The normal position of the parts is best seen in Figs. 1 and 2. When it is desired to operate the tabulating mechanism the tabulating key 83 is depressed, thereby, through the link 79, operating the lever 74 and raising the rack lifter 71 and the stop lifter 69. As the rack lifter is raised the lifting shoes 72 engage with the feed rack 25, swinging the latter upward about its pivots 27 and out of engagement with the feed pinion 28, thereby releasing the carriage and permitting it to be drawn freely leftward under the influence of the spring drum 41. At the same time the stop lifter 69 swings the stop arm 63 upward about its pivot 59 against the pressure of the spring 68, and swings the stop arm 62 downwardly about the pivot 59 until the working face 66 is in the path of the contact portions 43^a of the adjustable stops 43. The parts will now be in the position shown in Fig. 4. The carriage will move freely or "jump" leftward until the first stop 43 to the right of the working face 66 contacts with the latter, thereby preventing the further longitudinal movement of the rack bar 42. The carriage, however, will continue to move in printing direction, compressing the spring 51, until the inner end of the bushing 48 contacts with the shoulder 47 of the rack bar 42. The tabulating key 83 may then be released, the parts being restored to normal position under the influence of gravity and the spring of the rack 25, the stop spring 68 and the spring 77. As soon as the contact face 66 of the rotary tabulating stop 60 has swung upwardly far enough to disengage from the co-operating carriage stop 43 the rack bar 42 will be moved leftward by the compressed spring 51 until the head of the screw 52 engages with the bottom of the countersink in the bushing 48. It will be seen that the rack bar 42 has a slight longitudinal movement independent of the platen carriage, the amount of this movement being limited by stops and being equal to the space shown in Fig. 3 between the shoulder 47 and the inner end of the bushing 48. This slight independent movement of the rack bar 42 carries the co-acting stop 43 to the left of the contact arm 62, the construction being such as to provide considerable clearance between the co-acting tabulating stops and not to necessitate that said stops should be made so thin as to render them too weak for practical work. This is especially advantageous in view of the fact that the stop member 60 is a casting. When the parts have been restored to normal position as above explained, the desired printing

operations may be performed and thereafter the tabulating devices may be operated as before to bring the carriage to the next desired columnar position.

It will be seen that I provide an efficient tabulating mechanism of few parts and one which may be readily assembled in the machine. I do not, however, desire to be limited to the precise construction shown and it will be understood that various changes may be made in the construction and arrangement of different parts within the scope of my invention.

What I claim as new and desire to secure by Letters Patent, is:

1. In a typewriting machine, the combination of a carriage, carriage feeding mechanism including a movable feed rack, a column stop mounted on said carriage, a co-operating tabulating stop mounted on a fixed part of the machine, a rack lifter adapted to move said rack to release the carriage, and an extension on said rack lifter engaging said tabulating stop and adapted to move said tabulating stop to operative position. 90

2. In a typewriting machine, the combination of a carriage, carriage feeding mechanism including a movable feed rack, a column stop mounted on said carriage, a tabulating stop mounted on a fixed part of the machine, a sliding rack lifter having rack lifting shoes an extension fixedly related with said rack lifter and engaging said tabulating stop, and a finger key at the front of the machine adapted to actuate said rack lifter and its extension to release the carriage and move said tabulating stop to operative position. 95

3. In a typewriting machine, the combination of a carriage, carriage feeding mechanism including a pivoted feed rack, a column stop on the carriage, a tabulating stop pivoted to a fixed part of the machine, a slideable rack lifter, an extension from said rack lifter engaging said tabulating stop, a lever fulcrumed on a fixed part and having one of its arms pivotally connected directly with said rack lifter, a link pivotally connected with the other arm of said lever, and a key lever fulcrumed in the base of the machine and having a finger key at the front thereof, said key lever being pivotally connected with said link. 110

4. In a typewriting machine, the combination of a carriage comprising a rigid frame bar arranged at the rear side thereof, brackets fixed directly to said frame bar of said carriage, a rack bar slidably mounted in said brackets, a spring constantly tending to press said rack bar in the direction of letter space feeding movement, a column stop adjustable on said rack bar, a carriage guide rail fixedly mounted on the frame of the machine, a bracket secured thereto, a tabulating stop pivotally mounted in said bracket and normally spring pressed out of the path of said 125

column stop, and means for releasing said carriage and moving said tabulating stop into position to coöperate with said column stop.

5. In a typewriting machine, the combination of a carriage, brackets fixedly secured directly to the rear bar of said carriage, a rack bar slidably mounted in said brackets, a spring constantly tending to press said rack bar in the direction of letter space feeding movement, a column stop adjustable on said rack bar, a carriage guide rail fixedly mounted on the frame of the machine, a bracket secured thereto, a tabulating stop pivotally mounted in said bracket and normally spring 10 pressed out of the path of said column stop, carriage feeding mechanism including a feed rack pivoted on said carriage, a rack lifter adapted to move said feed rack to release said carriage and having an extension for operating said tabulating stop, and means operable from the keyboard of the machine for actuating said rack lifter and its extension.

6. In a typewriting machine and in a tabulating mechanism, the combination of a carriage having a rear bar and brackets fixed directly thereto and projecting rearwardly therefrom, a rack bar slidably mounted in said brackets, a column stop adjustable on said rack bar, carriage guide rails, curved 25 brackets to which said guide rails are secured, the construction being such that the rack bar and its supporting brackets may move freely from side to side of the machine on the guide rails and past said curved supporting brackets, a tabulating stop pivotally mounted on one of said guide rails, carriage feeding mechanism, and means for releasing said carriage from its feeding mechanism and for causing a coöperation between said tabulating and 30 column stops.

7. In a typewriting machine and in a tabulating mechanism, the combination of a carriage, brackets thereon, and a stop rack bar journaled in said brackets, said rack bar having 35 a tongue and groove connection with one of said brackets, a threaded bushing adjust-

able in the other bracket and receiving a reduced end of said rack bar, a coiled spring surrounding the reduced end of said rack bar and surrounded by said bushing and constantly tending to press the rack bar in printing direction, and a stop to limit the movement of said rack bar in printing direction under the influence of said spring.

8. In a typewriting machine and in a tabulating mechanism, the combination with a column stop and a tabulating stop, said tabulating stop being a casting comprising a hub portion and a stopping arm projecting from said hub portion and having a detachable 50 stopping face secured thereto, of supports for said stops, means for affording a limited motion of one of said stops relative to its support when the stops come into engagement, and a spring for restoring the movable part 55 to normal position when the stops are out of engagement, whereby a clearance of said stops is provided.

9. In a typewriting machine, the combination of a carriage, carriage feeding mechanism including a movable feed rack, a column stop bar extending lengthwise of the carriage and secured thereto, a plurality of column stops adjustable lengthwise of said 60 stop bar, a coöperating tabulating stop secured to a fixed part of the machine and pivoted to swing into and out of the path of travel of the column stops on the carriage, a key operated feed rack lifter arranged beneath said pivoted tabulating stop, and a device extending beyond said lifter for moving said tabulating stop into operative position when the feed rack lifter is operated to disengage the carriage.

Signed at Syracuse, in the county of Onondaga, and State of New York, this 18th day of November A. D. 1905.

EDWIN E. BARNEY.
